UNITED STATES PATENT OFFICE.

WILLIAM ACKERMAN, OF BROOKLYN, NEW YORK, ASSIGNOR TO MERGENTHALER LINOTYPE COMPANY, A CORPORATION OF NEW YORK.

TYPOGRAPHICAL MACHINE.

Application filed May 19, 1924. Serial No. 714,230.

To all whom it may concern:

Be it known that I, WILLIAM ACKERMAN, a citizen of the United States, residing at Brooklyn, in the county of Kings and State 5 of New York, have invented certain new and useful Improvements in Typographical Machines, of which the following is a specification.

This invention relates to typographical 10 machines, such as linotype machines of the general organization represented in U. S. Letters Patent No. 436,532, to O. Mergenthaler, wherein circulating matrices are released from a magazine in the order in 15 which their characters are to appear in print and then assembled in line, the composed line transferred to the face of a mold, the mold filled with molten metal to form a slug or linotype against the matrices 20 which produce the type characters thereon, and the matrices thereafter elevated and returned through distributing mechanism to the magazine from which they started. More particularly, it relates to that class of 25 machines equipped with a plurality of magazines containing matrices of different forms or fonts and a smaller plurality of simultaneously operating distributors capable of working in conjunction with different groups of magazines. The Billington 30 Patent No. 1,427,511 deals with machines of this class and provides an automatically controlled selecting mechanism which insures the delivery to the distributors of matrices of the particular forms or fonts contained in the magazines with which the distributors are for the time being in co-operation.

The present invention follows along the 40 same lines as that disclosed in the Billington patent, and contemplates an improved form of selecting mechanism, the general idea being to provide a simple, compact and economical construction, highly efficient in 45 operation and capable of being applied to the regular linotype machines with the minimum of change. The exact nature of the improvements and the advantages derived therefrom will best be understood from the 50 detailed description to follow.

Referring to the drawings:

Fig. 1 is a side elevation of the upper portion of a linotype machine equipped with the improvements;

Fig. 2 is a rear elevation on an enlarged

scale of the improved matrix separating mechanism;

Fig. 3 is a vertical section taken through said mechanism;

Fig. 3^a is a detail section taken on the line 60 3^a—3^a of Fig. 3; and

Fig. 4 is a perspective view showing the manner in which the matrix separating mechanism is controlled from the magazines. 65

In the preferred embodiment illustrated, the machine is equipped with four magazines A, containing matrices X of respectively different forms or fonts, and two like distributors B, which distribute the matrices according to character. The magazines are mounted in the so-called shift frame A¹, which is arranged to be moved upwardly and downwardly in the machine frame in the well-known manner to bring 70 any selected pair of adjoining magazines into operative relation to a pair of magazine entrances B¹ leading from the two distributors. The matrices are delivered to the respective distributors through tubes or 75 chutes C¹ leading from a preliminary distributor C, which separates the matrices according to form or font and drops them into one or the other of the tubes. The matrices are fed to the preliminary distributor, one at a time, from a distributor box D, which receives the composed lines after casting from a second elevator D¹. As ordinarily, the preliminary distributor C comprises a distributor bar E formed with 80 groups of teeth E¹ and intermediate blank portions E², a set of matrix conveying screws G, and a series of selector bridges F formed with matrix supporting ridges F¹. 85

In passing through the distributor, the matrices X are suspended from the teeth E¹ by their tooth combinations X¹ except at the blank portions E² where they are sustained at their lower ends by the ridges F¹ of the selector bridges F. The ridges F¹ vary in 90 number or arrangement on the different selector bridges and cooperate with corresponding cuts or notches X² formed in the lower ends of the matrices of the different fonts, the arrangement being such that 95 when a matrix reaches the bridge to which its notches correspond, it settles astride the ridges of this bridge out of engaging relation to the teeth on the distributor bar 100 and drops through the space between the 105

bridges into the delivery chute leading to the appropriate distributor. The foregoing parts and their mode of operation, except as hereinafter pointed out, are or may be 5 the same as embodied in the commercial Model 9 Linotype, or as illustrated in various patents issued to John R. Rogers.

According to this invention, the preliminary distributor C is provided with four selector bridges F, one for each of the magazines A, and the ribbed bar E is formed with but two blank portions E², one for each of the distributors B, provision being made whereby different pairs of bridges may 10 be located in operative position below the two blank portions to correspond with the different pairs of magazines brought into cooperation with the distributors. In the present instance, the several bridges are carried 15 by cross-blocks H¹ projecting rearwardly from an angular supporting slide H mounted for longitudinal adjustment in a corresponding guideway H² formed in the front wall of the preliminary distributor. 20 The forward side of the guideway is constituted by a removable wear-plate H³ set in position by means of screws H⁴. Fixed stops H⁵ and H⁶ are located at the opposite ends of the guideway to limit the extent of 25 adjustment of the supporting slide in opposite directions, the stop H⁵ serving to arrest the slide with the first and second bridges in operative position and the stop H⁶ serving to arrest the slide with the third 30 and fourth bridges in operative position. When adjusted midway between the two stops, the slide will present the second and third bridges in operative position, this being the condition illustrated in the drawings. 35 By thus setting the supporting slide in one or another of its three different positions, the matrix separating function of the preliminary distributor may be varied to correspond to whatever pair of magazines 40 is brought into cooperation with the two main distributors, it being noted that the two intermediate bridges under different conditions of adjustment are each located at one time below the first and at another time 45 below the second blank portion of the distributor bar, whereas the first and fourth bridges under similar conditions of adjustment are either located beneath the first and second blank portions, respectively, or 50 are out of operative position entirely. In this connection, it is pointed out that the last bridge of the series might be made plain or without ridges at all, inasmuch as it serves to direct matrices into the second delivery tube only. In such event, however, 55 any matrices reaching that bridge, irrespective of their form, would pass into the delivery tube and find their way back into the appropriate magazine. It is, therefore, 60 advantageous to provide the last bridge, like

the others, with the supporting ridges, so that only matrices of corresponding form will be allowed to pass into the delivery tube. Those matrices which are rejected by the last bridge simply pass out of the preliminary distributor and drop into a pi-tube. 70 As will be noted, the individual bridges F are connected to their supporting blocks H¹ by dove-tails f which permit them to be readily removed for interchange or replacement to correspond with a similar interchange or replacement of the magazines. In effecting the removal of the bridges, the rear wall of the preliminary distributor is swung up out of the way, as indicated by the dotted 75 lines in Fig. 3.

While the required adjustments of the bridge supporting slide might be effected manually, it is preferred to carry them out automatically in order to insure the delivery 80 of the matrices to their appropriate distributors at all times. Accordingly, as a convenient means for accomplishing this result, there is employed a bell crank lever J, centrally pivoted to the machine frame as 85 at J¹ and arranged with its upper end loosely engaged in a socket or recess H⁷ of the supporting slide. At its lower end, the bell crank lever is pivotally connected by a link J² to the rear end of a rocking lever 90 J³, which is pivoted at its forward end, as at J⁴, to a supporting bracket J⁵ fixed to the machine frame. Between its ends, the rocking lever J³ is provided with a roller J⁶ arranged to track upon a cam plate 95 J⁷ carried by the magazine shift frame A¹, said cam plate being formed with high and low surfaces J⁸ J⁹, respectively. A spring J¹⁰, pulling upwardly on the rocking lever serves to maintain its roller in engagement 100 with the cam plate and tends constantly, through the connections described, to shift the bridge supporting slide toward the left 105 in Figs. 2 and 4. The construction and arrangement of the parts is such that when the middle pair of magazines is brought 110 into cooperation with the distributors B, the low surface J⁹ of the cam plate is brought into engagement with the roller J⁶ of the rocking lever J³ and the latter rocked 115 downwardly to place the supporting slide H in its intermediate position, with the second and third bridges F in operative position below the two blank portions E² of the distributor bar E, such being the condition 120 of the parts as illustrated in the drawings. Under such conditions, the preliminary distributor will function to carry out the separation of the matrices belonging to the two magazines in use, delivering those 125 matrices into one or the other of the two delivery tubes C¹, according to form or font. If, however, the magazine shift frame is moved to connect the two upper 130 magazines with the distributors, the high

surface J^8 of the cam plate is engaged with the roller J^6 and the lever J^3 rocked downwardly to a further extent so as to adjust the supporting slide up against the right-hand stop H^6 , thereby placing the last two bridges beneath the blank portions E^2 and adapting the preliminary distributor to carry out the separation of the matrices according to form as contained in the two upper magazines. When, now, the magazine shift frame is moved to connect the two lower magazines to the distributors, the cam plate J^7 is carried entirely out of engagement with the rocking lever J^3 , allowing the spring J^{10} to rock the lever J^3 upwardly and shift the supporting slide up against the left-hand stop H^5 , thereby placing the first two selector bridges beneath the two blank portions E^2 and adapting the preliminary distributor to carry out the separation of the matrices according to form as contained in these two lower magazines. It will thus be seen that the position of the bridge supporting slide is controlled by that of the magazines, the matrix separating function of the preliminary distributor being varied automatically in accordance with the variation of the cooperating function of the two main distributors.

It has been seen that the adjustment of the bridge supporting slide in one direction is effected by the spring J^{10} , which is desirable in permitting the parts to yield in the event of obstruction being offered to the movement of the slide, as for instance due to a misplaced matrix. In order to provide for the yielding of the parts under similar conditions when the slide is adjusted in the opposite direction, the connecting link J^2 is constructed of two relatively movable parts, one a rod j fitted into a bar j' , which latter is formed with a recess j^2 containing a spring j^3 bearing at one end against a collar j^4 on the lower end of the rod j , and bearing at its opposite end against the upper wall of the recess. The collar j^4 is normally held in engagement with the lower wall of the recess so as to transmit the upward movement of the rocking lever J^3 to the bell crank lever J , but, as will be obvious, when undue resistance is offered to the downward movement of the rocking lever by the cam plate J^7 , the bar j' will be permitted to slide downwardly along the rod j , compressing the spring j^3 against the collar j^4 , which remains stationary because of the obstruction.

It has also been seen that the two fixed stops H^5 and H^6 serve to locate the bridge supporting slide definitely in its two terminal positions. In order to locate it with equal certainty in its intermediate position, there is employed a spring actuated pointed detent K mounted in the framework in position to engage in a V-shaped notch of a plate K^1 attached to the upper arm of the bell crank lever J (see particularly Fig. 3^a). The inclined sides of the V-shaped notch permit the ready disengagement of the detent as the slide is adjusted in either direction from its intermediate position. At opposite sides of the V-shaped notch the plate K^1 is formed with beveled surfaces K^2 , which facilitate the engagement of the detent in the notch.

It is pointed out that the selector bridges F , which are located below the distributor bar E or along the path of the matrices, are adjustable longitudinally of the bar or in a direction parallel with the matrix path to locate different groups thereof beneath the two blank portions of the bar. This arrangement is very advantageous in carrying out the objects of the invention as previously recited, and, moreover, provides for the proper cooperation between the ridges on the selector bridges and the notches in the bottoms of the matrices, it being obvious that such cooperation depends upon the accurate lateral location of the bridges as is secured by the longitudinal guideway in which the supporting slide is located.

In the accompanying drawings, the invention has been shown merely in preferred form and by way of example and obviously many changes and alterations may be made therein without departing from the spirit of the invention. For instance, while the machine illustrated deals with two distributors operating simultaneously in conjunction with a plurality of magazines, operable in pairs, the invention is equally applicable to, say, three or four distributors in use with a plurality of magazines operable in groups or series, each comprising a number of magazines corresponding to that of the distributors. Again, in the machine illustrated, the arrangement is such that three different pairs of magazines may be brought into use alternatively, whereas the arrangement might readily be modified to provide for the alternative use of a greater or less number of pairs of magazines, it being apparent, for instance, that if but two pairs of magazines are employed, the bridge supporting slide would need to be set in only two different operative positions. Moreover, the selection of the magazines in pairs or groups might be effected other than by shifting the magazines, as for example by the movement of the distributors instead. These and various other modifications will readily suggest themselves to those skilled in the art and still be comprised within the scope of the invention. It should be noted, therefore, that the invention is not limited to any specific form or embodiment, except in so far as such limitations are specified in the claims.

Having thus described my invention, its

construction and mode of operation, what I claim and desire to secure by Letters Patent of the United States, is as follows:

1. Matrix separating mechanism including a plurality of selector bridges arranged along the matrix path and adjustable in a direction parallel with said path to locate one or another in operative position.
2. Matrix separating mechanism comprising a toothed distributor bar formed at one point in its length with a blank portion, a plurality of selector bridges underlying the distributor bar, and means for adjusting the selector bridges longitudinally of the distributor bar to locate one or another beneath its blank portion.
3. Matrix separating mechanism comprising a toothed distributor bar formed at one point in its length with a blank portion, a plurality of selector bridges underlying the distributor bar, and a supporting slide carrying the selector bridges and adjustable longitudinally of the distributor bar to locate one or another thereof beneath its blank portion.
4. Matrix separating mechanism comprising a toothed distributor bar formed at one point in its length with a blank portion, a plurality of selector bridges underlying the distributor bar, a supporting slide carrying the selector bridges and adjustable longitudinally of the distributor bar to locate one or another thereof beneath its blank portion, and a fixed stop arranged to arrest the supporting slide in one of its operative positions.
5. Matrix separating mechanism comprising a toothed distributor bar formed at one point in its length with a blank portion, a plurality of selector bridges underlying the distributor bar, a supporting slide carrying the selector bridges and adjustable longitudinally of the distributor bar to locate one or another thereof beneath its blank portion, and a pair of fixed stops arranged to arrest the supporting slide in different operative positions.
6. Matrix separating mechanism comprising a toothed distributor bar formed at one point in its length with a blank portion, a plurality of selector bridges underlying the distributor bar, a supporting slide carrying the selector bridges and adjustable longitudinally of the distributor bar to locate one or another thereof beneath its blank portion, and a fixed guideway in which the supporting slide is mounted.
7. Matrix separating mechanism comprising a toothed distributor bar formed at one point in its length with a blank portion, a plurality of selector bridges underlying the distributor bar, and a supporting slide carrying the selector bridges and adjustable longitudinally of the distributor bar to locate one or another thereof beneath its blank portion, the said selector bridges being detachably connected to the supporting slide to permit their ready replacement or interchange.
8. Matrix separating mechanism comprising a toothed distributor bar formed at different points in its length with blank portions, a plurality of selector bridges underlying the distributor bar, and means for adjusting the selector bridges longitudinally of the distributor bar to locate different groups thereof beneath its blank portions.
9. Matrix separating mechanism comprising a toothed distributor bar formed at different points in its length with blank portions, a plurality of selector bridges underlying the distributor bar, and a supporting slide carrying the selector bridges and adjustable longitudinally of the distributor bar to locate different groups thereof beneath its blank portions.
10. In a machine such as described, the combination with a plurality of main distributors and a separating mechanism for directing matrices to the respective distributors, according to form, said mechanism including a plurality of selector bridges arranged along the matrix path and adjustable in a direction parallel with said path to locate one or another in operative position, of a magazine containing matrices of a given form, means for connecting said magazine with one or another of the distributors, and automatic means for effecting the proper adjustment of the selector bridges to provide for the delivery of the matrices contained in said magazine to the particular distributor with which it is connected.
11. In a machine such as described, the combination of a plurality of magazines, a smaller plurality of main distributors, and means whereby the several distributors may be operatively connected to different groups of magazines, with matrix separating mechanism including a toothed distributor bar formed with a blank portion at one point in its length, and a plurality of selector bridges underlying said bar and adjustable longitudinally thereof to locate one or another beneath said blank portion, together with automatic means for adjusting the selector bridges to correspond with the particular group of magazines selected.
12. In a machine such as described, the combination of a plurality of magazines, a smaller plurality of main distributors, and means for moving the magazines to bring different selected groups thereof into operative relation to the several distributors, with matrix separating mechanism including a toothed distributor bar formed with a blank portion at one point in its length and a plurality of selector bridges underlying said bar and adjustable longitudinally

thereof to locate one or another beneath said blank portion, together with means controlled by the movement of the magazines for adjusting the selector bridges to correspond with the particular group of magazines selected.

13. In a machine such as described, the combination of a plurality of magazines, a smaller plurality of main distributors, and means whereby the several distributors may be operatively connected to different groups of magazines, with matrix separating mechanism including a toothed distributor bar formed at different points in its length with as many blank portions as there are main distributors, and a plurality of selector bridges, one for each of the magazines, underlying the distributor bar and adjustable longitudinally thereof to locate different selected groups beneath said blank portions, together with automatic means for adjusting the selector bridges to correspond with the particular group of magazines selected.
14. In a machine such as described, the combination of a plurality of magazines, a smaller plurality of main distributors, and means for moving the magazines to bring different selected groups thereof into oper-

ative relation to the several distributors, with matrix separating mechanism including a toothed distributor bar formed at different points in its length with as many blank portions as there are main distributors, and a plurality of selector bridges, one for each of the magazines, underlying the distributor bar and adjustable longitudinally thereof to locate different selected groups beneath said blank portions, together with means controlled by the movement of the magazines for adjusting the selector bridges to correspond with the particular group of magazines selected.

15. In a machine such as described, the combination of the movable magazines A, the main distributors B, the preliminary distributor C including the longitudinally adjustable bridge supporting slide H, and means actuated by the movement of the magazines for adjusting the bridge supporting slide, said means including the bell crank lever J, connecting link J², rocking lever J³, cam plate J⁷, and spring J¹⁰.

In testimony whereof I have affixed my signature hereto.

WILLIAM ACKERMAN.
